(57) **CLAIM**

The ornamental design for a hook assembly, as shown and described.

DESCRIPTION

FIG. 1 is a front isometric view of the hook assembly; FIG. 2 is a rear isometric view of the hook assembly of FIG. 1; FIG. 3 is a front view of the hook assembly of FIG. 1; FIG. 4 is a rear view of the hook assembly of FIG. 1; FIG. 5 is a right side view of the hook assembly of FIG. 1; FIG. 6 is a left side view of the hook assembly of FIG. 1; FIG. 7 is a top view of the hook assembly; and, FIG. 8 is a bottom view of the hook assembly.

The broken lines depict portions of the hook assembly that form no part of the claimed design.
